UNITED STATES PATENT OFFICE.

JEAN FRANÇOIS BOYER, OF BOSTON, MASSACHUSETTS, ASSIGNOR TO THE BOSTON WATCH CASE COMPANY, OF SAME PLACE.

DESIGN FOR A WATCH-CASE.

SPECIFICATION forming part of Design No. 14,866, dated March 11, 1884.

Application filed February 16, 1883. Term of patent 7 years.

To all whom it may concern:

Be it known that I, JEAN FRANÇOIS BOYER, a citizen of the United States, residing at Boston, in the county of Suffolk and State of Massachusetts, have invented certain new and useful Improvements in a Design for Watch-Cases; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 In this design the outer margin of the case adjoining the "center," so called, is oblique or sloping, as shown at *a*, and this sloping margin is subdivided into a series, *b b*, of flat faces of equal length and breadth. The circumference of the case thus becomes polygonal in outline, in lieu of an unbroken circle,

as shown in the accompanying drawings, embodying this design, in which—

Figure 1 represents a side elevation, and Fig. 2 an end elevation, of a watch-case containing my invention.

The "center," so called, of the watch-case proper is likewise subdivided into facets, which correspond in number and position with the facets on the case.

The cap may be ornamented or engraved after any of the usual methods.

I claim—

The design for watch-cases herein described, and as shown by the accompanying drawings.

In testimony whereof I affix my signature in presence of two witnesses.

JEAN FRANÇOIS BOYER.

Witnesses:

H. E. LODGE,
THOS. T. BAILEY.
